US00D872122S

(12) **United States Design Patent** (10) Patent No.: **US D872,122 S**
Altonen et al. (45) Date of Patent: ** Jan. 7, 2020

(54) **DISPLAY SCREEN OR PORTION THEREOF WITH GRAPHICAL USER INTERFACE**

(71) Applicant: **Lutron Technology Company LLC**,
Coopersburg, PA (US)

(72) Inventors: **Gregory S. Altonen**, Easton, PA (US);
Jason C. Killo, Emmaus, PA (US);
Brad M. Kreschollek, Bethlehem, PA (US); **Madia L. Rivera**, Bethlehem, PA (US)

(73) Assignee: **Lutron Technology Company LLC**,
Coopersburg, PA (US)

(**) Term: **15 Years**

(21) Appl. No.: **29/633,663**

(22) Filed: **Jan. 15, 2018**

(51) LOC (12) Cl. **14-04**

(52) U.S. Cl.

USPC **D14/488**; D14/485; D14/489

CLAIM

We claim the ornamental design for a display screen or portion thereof with graphical user interface, as shown and described.

DESCRIPTION

The sole FIGURE shows a display screen or portion thereof with graphical user interface according to our new design. The broken line showing of a display screen or portion thereof is included for the purpose of illustrating portions of the article and forms no part of the claimed design.

1 Claim, 1 Drawing Sheet
